AMUSEMENT RIDE CAR

Robert H. Gurr, North Hollywood, Calif., assignor to
Disneyland, Inc., Anaheim, Calif., a corporation of
California

Filed Jan. 18, 1960, Ser. No. 59,084

Term of patent 14 years

(Cl. D34—15)

Figure 1 is a three-quarter front perspective view of an amusement ride car showing my new design;

Figure 2 is a front view of said car;

Figure 3 is a rear view of said car;

Figure 4 is a top plan view of said car; and

Figure 5 is a three-quarter rear perspective view of said car.

I claim:

The ornamental design for an amusement ride car, substantially as shown.
